NICOTINE AND MOISTURE ABSORBING
PIPE

Hans Hoelk, Brooklyn, N. Y.

Application March 31, 1936, Serial No. 71,820

4 Claims. (Cl. 131—12)

My present invention relates to smoking pipes, and aims to provide a device of the general character indicated, which is simple in construction, easy and economical to fabricate and assemble, and which presents certain advantages over existing smoking pipes of a similar nature, which will be set forth in later portions of this specification.

In the accompanying specification I shall describe, and in the annexed drawing show, an illustrative embodiment of the smoking pipe of the present invention. It is, however, to be clearly understood that I do not wish to be limited to the exact details of construction shown and described herein for purposes of illustration only, inasmuch as minor changes therein may be made without the exercise of the inventive faculties, and within the scope of the claims hereto appended.

20 In the drawing:—

Fig. 1 is a longitudinal, sectional view, taken through the center of a smoking pipe, made in accordance with the present invention; and

Fig. 2 is a perspective view of the stem of such pipe showing more clearly the nature of the attachment which will be more specifically referred to in the detailed description.

Before describing my invention in detail, I deem it advisable, briefly, to refer to the prior art in the field to which the present invention relates, to point out some of the disadvantages thereof, and the manner in which the present invention overcomes the same.

There are in existence at the present time a number of so-called "drinkless" pipes. These pipes have for their object the preventing of drawing into the smoker's mouth the moisture which normally collects in a smoking pipe, and the nicotine and other impurities normally present in smoking tobacco. I have discovered that such "drinkless" pipes have certain disadvantages. In the first place, for the most part, such pipes contain a filtering device which is supposed to absorb the moisture and nicotine and through the center of which the smoke is drawn from the bowl to the smoker's mouth. I have found that such pipes have a tendency to clog thereby preventing an easy draw and eventually clogging entirely so as to require very frequent changing of the filtering device. I have further found that in view of the manner in which the filtering device is set in the pipe it is ineffective for absorbing all of the moisture, and a good deal of the moisture gets past the filter, goes through the stem, and eventually enters the

smoker's mouth. Furthermore, in view of the fact that it is necessary, quite frequently, to change the filtering device, it is rather an expense to say nothing of the annoyance and unclean and unsanitary way in which the filter must be removed. By means of the present invention these disadvantages are entirely removed, and a pipe is provided in which the filtering device is very readily inserted and removed, effectively absorbs the moisture, nicotine and other impurities, and is very inexpensive. Other objects and advantages will become obvious to those skilled in the art to which the present invention relates as the detailed description thereof progresses.

Referring now more in detail to the illustrative embodiment of the present invention, and with particular reference to the drawing illustrating the same, the numeral 5 generally designates a smoking pipe consisting, broadly, of three (3) portions, the stem 6, the bowl 7 and the attachment 8.

The bowl 7 is provided with a passage 9 leading to a chamber 10 within which it is intended to fit the attachment 8. The stem 6 is conventional and is provided with a central passage 11 which is stepped at 12 to receive the attachment 8.

The attachment 8 consists of a cylindrical plug 13 reduced at 14 so as to permit its being fixed within the step portion 12 of the stem 6. The cylindrical plug 13 is cut away at its front portion 15 so as to present a small flattened surface 16, the sides 17 of which are sloped downwardly so that any moisture which might gather on the small flattened surface 16 will readily roll down the sides 17 and not enter the opening 18 which leads to the passage 19 in register with the passage 11 of the stem 6. Extending outwardly from the front wall of the plug 13 is a gradually reduced spindle 20, the outer end of which is adapted to pass through the passage 9 and extends slightly within the bowl 7. By so arranging the spindle 20, the opening to the passage 9 is prevented from clogging.

While any type of filtering device may be utilized in conjunction with the attachment 8, I prefer to use an ordinary pipe cleaner. All that it is necessary to do to use such a filter with the attachment 8, is to place one end 21 thereof into the small opening 22 in the front wall of the plug 13 of the attachment, and then wind the cleaner 23 about the spindle 20 as clearly shown in the drawing. The pipe may then be assembled so that the filtering device is within the chamber 10 and the action thereof, during smoking, becomes as follows:

Smoke drawn through the passage 9 from the

bowl enters the chamber 10 where it circulates about the filter 23, and comes into such intimate contact therewith that all of the moisture, nicotine and other impurities are removed therefrom and absorbed by such filter so that only pure smoke can enter the opening 18 which is positioned face upwardly and which leads to the passage 19, thence to the passage 11 and then to the smoker's mouth. Should any moisture still remain in the smoke when it reaches the flattened portion 16 of the attachment, the same is deposited upon such flattened area and immediately rolls off the same down the sloping sides 17, and never reaches the smoker's mouth. When it is desired to change the filter, all that it is necessary to do is to remove the bowl 7 from the stem 6 and with a match-stick or any other convenient device slide the filter 23 off the spindle 20. A new one is readily secured in place and the pipe is again ready to be smoked.

This completes the description of the aforesaid illustrative embodiment of the present invention. It is believed that it will be obvious from such description that the smoking pipes of the present invention are simple in construction, easy and economical to fabricate and assemble and admirably adapted to perform the functions set forth from time to time as the detailed description progressed.

30 Other objects and advantages of the present invention will readily appear to those skilled in the art to which the present invention relates.

What I claim as my invention is:

1. In a moisture and nicotine absorbing pipe, 35 the combination with the bowl and stem there-

of, of an attachment having a passage communicating between the stem and the bowl, said attachment including a filter-support and a recess offset from the longitudinal axis of said filter-support and a filter element anchored in said recess and carried by and wrapped about said support. 5

2. In a moisture and nicotine absorbing pipe, the combination with the bowl and stem thereof, of an attachment having a passage communicating between the stem and the bowl, said attachment including a cylindrical plug cooperable with the stem and bowl, a filter-support extending from said plug, and a replaceable filter element anchored at one end in said plug and being carried by and wrapped about said filter-support. 10

3. In a moisture and nicotine absorbing pipe, the combination with the bowl and stem thereof, of an attachment having a passage communicating between the stem and the bowl, said attachment including a cylindrical plug cooperable with the stem and bowl, a spindle extending from said plug into the bowl and a replaceable filter element anchored at one end in said plug and being carried by and wrapped about said spindle. 20

4. An attachment for smoking pipes comprising a cylindrical plug having a flattened portion adjacent its forward wall provided with sloping sides and a filter-anchoring opening in its forward wall, a spindle extending outwardly from said forward wall, and a replaceable filter element having one end thereof anchored in said forward wall, and being carried by and wrapped about said spindle. 25 30
